STARTING CIRCUITS

Lloyd Smede, Pittsburgh, Pa., assignor to Westinghouse Electric & Manufacturing Company, East Pittsburgh, Pa., a corporation of Pennsylvania

Application May 3, 1933, Serial No. 669,273

27 Claims. (Cl. 175—363)

My invention relates to control apparatus and it has particular relation to control apparatus utilized in the operation of electric discharge devices of the type incorporating a starting electrode.

An electric discharge device of the type to which my invention particularly applies, in general, comprises a plurality of principal electrodes preferably enclosed in a gas-tight envelope between which an electrical discharge is to pass. The discharge may be initiated by impressing a potential of predetermined magnitude between the principal electrodes. However, in the practice of my invention it is initiated by the cooperation of a starting electrode and one of the principal electrodes. The starting electrode is disposed adjacent to or in contact with the principal electrode with which it is to cooperate and it generally has a resistance which is high compared to the resistance of the cooperative electrode. To start the discharge between the principal electrodes, a comparatively heavy current is transmitted between the starting electrode and its cooperative electrode.

In the electric discharge devices that are utilized in the preferred practice of my invention, at least one of the principal electrodes is a conductive liquid or a suitable solid and the starting electrode is immersed therein. When a solid is utilized it is preferably but not necessarily a metal of the type that has a relatively high vapor tension at a relatively low temperature such as lead or tin. I have found that the starting electrodes also cooperate in a suitable manner with an electrode of iron or nickel although the vapor tension of such an electrode is not high.

More specifically, one of the principal electrodes in these electric discharge devices is mercury and the starting electrode is a rod of material having a resistivity high compared to mercury which is immersed in the mercury. To initiate a discharge between the principal electrodes of an electric discharge device of this type, a current is transmitted between the starting electrode and the mercury. This current is of such polarity that the starting electrode is positive electrically with respect to the mercury.

While the theory of the operation of the electric discharge devices of the type discussed hereinabove, is largely conjectural, it appears that the discharge is initiated by the ionization effect of a series of minute sparks which pass in the space between the mercury and the starting electrode when current is transmitted through the starting electrode. It will appear at once from this con-

sideration that to properly initiate the discharge, the starting electrode should not be wetted by the mercury, nor should it amalgamate with the mercury and in experimenting with the electric discharge devices discussed herein, I have verified this conclusion.

However, among the materials that I have found which may be suitably utilized as starting electrodes are a number which have a heterogeneous internal structure as distinguished from a homogeneous one. Such materials are not uniformly electrically conductive throughout but the conductivity is provided by a series of connected strings of particles extending from the upper surface of the material to the lower surface or to the sides thereof. In such a case, the starting electrode is not necessarily rendered inoperative by the wetting of the surface thereof, by the mercury or by the amalgamation of the surface with the mercury. In spite of the wetting of the surface of the electrode as a whole by the mercury or its amalgamation with the mercury the connected strings of particles may remain entirely unwetted by the mercury and may not amalgamate with it. As long as the strings of particles are unaffected by the mercury the starting electrode continues to function properly.

It will be seen from the above discussion that considerable care must be taken in selecting the electrodes that are utilized in the electric discharge devices and in providing for the transmission of a starting current between the starting electrode and the mercury. Since these currents are, in general, comparatively large, problems of considerable difficulty have arisen in providing the necessary starting apparatus. In accordance with the teachings of the prior art, the starting current is transmitted directly from the power source through the electrode in question. However, since the electrode is deleteriously affected by the reverse current which must necessarily pass therethrough when the discharge is initiated between the principal electrodes, a rectifier is ordinarily connected in series with the starting electrodes in the starting circuit. The rectifier is so connected that it passes current only in a direction such that when it is energized, the starting electrode is positive relative to the mercury. When current is thus transmitted through the rectifier and through the starting electrode, a discharge is initiated between the principal electrodes. After the discharge is initiated, the rectifier prevents the passage of current through the starting electrode

in a direction such that the starting electrode is negative relative to the mercury, and thereby protects the electrode from the deleterious effects of the reverse current.

- 5 In the discussion which follows the potential impressed between the principal electrodes of the electric discharge device shall be designated as the principal potential. Correspondingly the current transmitted through the starting electrode to initiate the discharge between the principal electrodes shall be designated as the starting current. Moreover, the potential of the mercury shall be taken as the reference potential. Thus a positive principal potential is impressed 10 on the electric discharge device when the mercury is negative electrically relative to the other principal electrode and a positive starting current is transmitted through the starting electrode when the current flows from the starting electrode to the mercury. The above set of conventions are provided on the assumption that, as is the case in the preferred practice of my invention, the electric discharge device is of the asymmetric type and has one mercury electrode 15 and one anode to cooperate with the mercury electrode. If the device is of the symmetric type and has two mercury electrodes with each of which starting electrodes cooperate each mercury electrode may be taken as an electrical reference point when it is negative relative to the other electrode.

In accordance with the teachings of the prior art, the rectifier is connected directly to the power source and the starting electrode is connected 35 in series with the power source through the rectifier. By reason of the variations in the elements appurtenant to the power source, the current transmitted through the rectifier and through the starting electrode is not, in general, uniform 40 and in consequence thereof, in apparatus of the prior art, the output of the electric discharge device varies over a considerable range.

It is to be understood that the starting electrode functions only to start the discharge between the principal electrodes. When starting current of proper polarity is transmitted between the starting electrode and the mercury, the discharge between the principal electrodes is initiated and it continues as long as the principal 45 potential is of proper magnitude and polarity to sustain the discharge. The polarity should be such that the mercury is negative relative to the other principal electrode, while the magnitude of the principal potential should be equivalent to the ionizing potential corresponding to the distance between the principal electrode and the character of the vapor in which the electrodes are immersed.

To attain satisfactory control of the output of 60 the electric discharge device, the practice has been to connect an alternating potential between the principal electrodes of the electric discharge device. If an alternating principal potential is provided, a discharge may, in general, be 65 initiated between the electrodes only during the intervals when half cycles of positive principal potential are impressed on the electric discharge device. If a pulse of positive starting current of proper polarity is transmitted between the starting electrode and the mercury during an interval 70 when the principal potential is positive, a discharge is initiated between the principal electrode and continues substantially during the remaining portion of the positive half cycle. The point 75 in the positive half cycle of principal potential at

which the discharge is initiated is dependent, of course, on the magnitude of the current transmitted between the starting electrode and the mercury and on the particular instant at which the current attains the proper magnitude. If the starting current varies over a wide range the current output of the electric discharge device correspondingly varies over a wide range. 5

In the starting apparatus constructed in accordance with the teachings of the prior art, the starting current has been found to vary over a considerable range. The variations appear to arise from variations in the circuits that cooperate with the rectifier and with the power source. For many purposes, the variations thus introduced into the output of the electric discharge device have rendered it rather unsatisfactory in its operation. 10

Another difficulty in the starting operation appears to arise from the character of the starting electrode which, as has been explained above, is often made of a heterogeneous material, composed of a mass of stringy electrical conducting paths. These stringy paths terminate in the mercury and of these a number terminate in the region of the meniscus of the mercury that is adjacent to the starting electrode. When the starting current is transmitted through the latter paths the terminals of the paths that just contact the mercury become hot, causing the mercury in their small spheres to evaporate. When the mercury evaporates a minute gap is formed between the mercury and the ends of the conducting paths and arcs are ignited across the paths and cause the discharge between the principal electrodes to be 30 initiated. 35

As the operation of the electric discharge device continues the terminals of the stringy conducting paths vary in dimension and location and by reason of this variation more or less current is required to initiate the discharge. If the terminals of the stringy paths are small in dimensions the current required for starting is small; on the other hand, if the terminals are extensive in area the current required for starting is comparatively 40 large. In general, sufficient current must be supplied to provide for any contingency and the minimum starting current which should be supplied for proper operation should be large enough to start the discharge for the most extensive terminals occurring in practice. 45

If, however, the starting current is supplied simply by connecting the starting electrode directly to the power source through a rectifier, the current supplied varies from its minimum 55 value to its maximum during an interval corresponding to a quarter-cycle of starting potential. If the terminals of the conducting strings are small in area, the necessary starting arc will be produced early in the quarter-cycle of starting current and the electric discharge device will become energized early in the quarter-cycle. If, on the other hand, the terminals are extensive in area the electric discharge device will start late in the quarter-cycle. As the character of the starting electrode is varied during operation the current output of the electric discharge device will therefore vary continuously. 60

It is accordingly an object of my invention to provide for electric devices of the type incorporating starting electrodes, starting apparatus for precisely and accurately controlling the current output. 70

Another object of my invention is to provide for electric discharge devices of the type incor- 75

porating starting electrodes, apparatus for supplying adequate starting current to the starting electrodes at the precise point in the half cycle of positive principal potential at which it is desirable that the starting current be supplied to provide the necessary or desirable output current.

A further object of my invention is to provide for electric discharge devices of the type incorporating starting electrodes, apparatus for applying starting currents of such high peak values as to definitely determine the point in the positive half cycle of principal potential at which the electric discharge device is to start, but of such short duration as to require conductors of comparatively small capacity for transmission.

Still another object of my invention is to provide for electric discharge devices of the type incorporating starting electrodes of heterogeneous internal structure, apparatus for applying a starting current impulse to the starting electrodes that shall be of such short duration and of such high amplitude that the electric discharge devices shall become energized in a time interval after the starting current is applied that shall be substantially independent of the character of the structure of the individual elements of the starting electrodes.

More concisely stated, it is an object of my invention to provide for a system of the type incorporating electric discharge devices equipped with starting electrodes, apparatus for supplying starting current to the starting electrodes which shall supply the current in such manner that the output of the electric discharge devices shall be uniform and shall be capable of accurate adjustment.

In accordance with my invention, the rectifier through which the starting current is transmitted is energized from a capacitor which is, in turn, charged by direct current pulsations transmitted from an alternating current power source through a second rectifier. The alternating potential impressed on the latter rectifier and the capacitor is in opposite phase relationship to the alternating potential that is impressed on the principal electrodes of the electric discharge device. The electric discharge device is, in the preferred practice of my invention, of the asymmetric type, and when the potential impressed between its electrodes is of such polarity that current is not transmitted therethrough, the potential impressed across the capacitor and the rectifier through which the capacitor is charged is of such polarity that the capacitor is being charged.

The rectifier through which the starting current is transmitted is equipped with a control electrode and the capacitor is connected in series with its principal electrodes with the mercury electrode of the electric discharge device and with the starting electrode. As has been explained hereinabove, the capacitor is charged during a negative half cycle of principal potential of the electric discharge device. During the charging interval the potential impressed between the control electrode and the principal electrodes of the rectifier associated with the starting electrode is maintained at such a value that the rectifier is deenergized. The capacitor is charged during a fraction of the negative half cycle of principal potential and thereafter the potential impressed between the principal electrodes of the rectifier associated with the starting electrode is sufficient to initiate a discharge between those electrodes. The potential applied

between the control electrode and the principal electrodes of the rectifier is so varied that the rectifier is capable of becoming energized at a point in the positive half cycle of principal potential of the electric discharge device which corresponds to the current output that is desired. When the control potential of the rectifier attains the requisite value, the rectifier becomes energized and the capacitor is discharged through the rectifier and through the starting electrode, and initiates the principal current in the electric discharge device.

In the following discussion the potential impressed between the control electrode and the cathode of the rectifier shall be designated as the control potential. The potential impressed between the anode and the cathode of the rectifier shall be designated as the principal potential of the rectifier and by analogy with the electric discharge device the potential of the cathode shall be taken as the reference potential. Moreover, the control potential at any principal potential above which the rectifier is just energized and below which it remains deenergized shall be designated as the limiting control potential.

The capacitor and the rectifier through which the starting current is transmitted should be of such character that the current impulse transmitted through the starting electrode is sufficient to initiate the discharge between the principal electrodes of the electric discharge device under most circumstances that are met in practice. For this reason, I have found that preferably the rectifier should be of the gas-filled type and the network including the rectifier, the capacitor and the starting electrode should be of such character that 50 to 100 amperes are transmitted through the starting electrode in a short interval of time during the starting operation. However, it should be noted that my invention has been utilized in systems where the starting current required is as low as 7 milliamperes and in systems in which the starting current required is greater than 100 amperes.

The novel features that I consider characteristic of my invention are set forth with particularity in the appended claims. The invention itself, however, both as to its organization and its method of operation, together with additional objects and advantages thereof, will best be understood when read in connection with the accompanying drawings in which:

Figure 1 is a diagrammatic view showing a preferred embodiment of my invention;

Figs. 2 and 3 are graphs illustrating the operation of Fig. 1;

Fig. 4 is a diagrammatic view showing a modification of my invention; and,

Fig. 5 is a graph illustrating the operation of a system such as is shown in Fig. 4.

The apparatus shown in Fig. 1 comprises an electric discharge device 1 having an anode 3, preferably of a material such as nickel or carbon, and a cathode 5, preferably of mercury, disposed in a chamber 7 that is preferably highly evacuated. A starting electrode 9 is immersed in the mercury 5. As has been explained hereinabove, the starting electrode 9 should have a resistivity high compared to the resistivity of the mercury 5 and should not be wetted by the mercury nor should it amalgamate with the mercury. I have found that for proper operation the starting electrode 9 should have a resistivity of at least 0.4 per cubic inch.

As can be seen from Fig. 1, if the starting elec-

trode 9 is not wetted by the mercury 5 and does not amalgamate therewith the meniscus 11 of the mercury in the region in which it is in contact with the starting electrode recedes from the 5 electrode and a minute gap 13 is provided between the mercury and the starting electrode. According to the present theory of the operation of the electric discharge device 1, when a starting current of proper polarity is transmitted between the starting electrode 9 and the mercury 5, minute sparks are generated in the gap 13 between the meniscus and the starting electrode, and by reason of the ionization produced by the 10 minute sparks, the discharge between the principal electrodes 3 and 5 of the electric discharge device is initiated. It is to be noted that if the starting electrode is not of proper character and the mercury amalgamates or wets the starting electrode 9, the meniscus 11 of the mercury 5 in 15 the region of its contact with the electrode will assume a concave contour and the necessary gap 13 between the mercury and the starting electrode will not be provided.

If, however, a starting electrode 9 of heterogeneous structure is utilized the mercury may wet the external surface of the electrode or amalgamate with it as has been explained hereinabove provided that it does not wet or amalgamate with the ends of the individual stringy conductors of which the starting electrode is composed.

It is to be understood, of course, that the above discussion is of a general theoretical character and may not, when the situation is better known, be found to represent the actual conditions. For this reason it should be understood that my invention is not to be limited by any particular theory of operation.

As to the proper materials which may be utilized for the starting electrodes 9, I have found that carbon, silicate carbide, boron carbide, boron, silicon boron and boron carbide mixtures and boron and carbon mixtures, yield satisfactory results. From the present state of my work with the electric discharge devices, it appears that carborundum (that is to say, silicon carbide) yields highly edifying results, and boron carbide, boron and mixtures of boron and carbon appear to be far more satisfactory even than silicon carbide.

To return to the apparatus shown in Fig. 1, the electric discharge device 1 is supplied with potential from a suitable power source (not shown) through a transformer 15, one section 17 of the secondary 19 of which is connected between the anode 3 and the cathode 5 thereof through a load 21 of any general character that might be energized through the electric discharge device.

The starting potential for the electric discharge device is provided by a capacitor 23 that is periodically charged from another section 25 of the secondary 19 through a rectifier 27 and is discharged through another rectifier 29 of the grid controlled type. The anode 31 of the grid controlled rectifier 29 is connected to one plate 33 of the capacitor 23 while the cathode 35 is connected to the starting electrode 9 of the electric discharge device 1 through a resistor 37 of suitable character. The other plate 39 of the capacitor 23 is connected to the mercury cathode 5 of the electric discharge device 1. The network 41 comprising the capacitor 23, the principal circuit of the grid controlled rectifier 29, the resistor 37, the starting electrode 9 and its co-

operative mercury electrode 5 has a predetermined time constant depending on the magnitudes of the various elements. By varying the resistor 37 in series with the grid controlled rectifier 29 the time constant of the network 41 may be varied. The time constant of the network 41 determines the rate at which the capacitor when charged is discharged through the network, and consequently determines when the principal current in the electric discharge device 1 will be 10 initiated.

The resistor 37 is utilized in the discharging network 41, by reason of the fact that the starting current must be supplied for at least a small interval of time before the discharge between the 15 principal electrodes 3 and 5 is initiated. If the starting current does not persist for at least this interval of time the electric discharge device fails to become energized in spite of the magnitude of the starting current. The time constant 20 of the starting network 41 is of such magnitude that the starting current persists for the necessary interval of time. The time interval is of course extremely small and in practice varies from 0 to 500 micro-seconds.

The capacitor 23 is connected in series with the rectifier 27 through which it is charged and with a resistor 43 of suitable character. The cathode 45 of the rectifier 27 is connected to the plate 33 of the capacitor 23 to which the anode 31 of the grid controlled rectifier 29 is connected and the anode 47 of the rectifier is connected to one terminal 49 of the section 25 of the secondary 19 whereby the capacitor 23 is charged. The network 51 including the section 25 of the secondary 35 19 through which the capacitor 23 is charged, the rectifier 27 through which it is charged, the capacitor 23 and the resistor 43, have a predetermined time constant which, in turn, determines the rate at which the capacitor 23 is 40 charged.

The section 25 of the secondary 19 through which the capacitor 23 is charged is so wound that the potential impressed across the network is in opposite phase relationship to the principal 45 potential impressed on the electric discharge device 1 and the potential impressed on the terminal 49 to which the anode 47 of the rectifier 27 is connected is 180° out of phase with the potential impressed on the terminal 53 to which the 50 anode 3 of the electric discharge device 1 is connected. Consequently when the potential of the anode 3 of the electric discharge device 1 is negative relative to the potential of the mercury cathode 5, the anode 47 of the rectifier 27 through 55 which the capacitor 23 is charged is positive relative to its cathode 45, and current is transmitted through the rectifier 27 to charge the capacitor. It will be seen that as long as the anode 3 of the electric discharge device 1 is negative the device 60 remains deenergized. During this interval the capacitor 23 is charged through the rectifier 27. In practice the resistor 43 in the charging network 51 is of such magnitude that the capacitor 23 is charged during a comparatively small fraction of the half cycle of positive potential applied to the charging network 51.

The control electrode 55 of the grid controlled rectifier 29 is connected to the anode 3 of the electric discharge device 1 through a portion 70 of the windings of a potentiometer 57, a suitable resistor 59 and the load 21. The potentiometer 57 is energized from a battery 60 and the potential of the control electrode 55 is in the preferred practice of my invention maintained 75

negative relative to the cathode 35 of the rectifier 29. By thus maintaining the control potential of the rectifier 29 negative the rectifier is maintained deenergized during any desired fraction of the half cycles of principal potential that are impressed on the electric discharge device 1. It is to be noted that during the negative half cycle of principal potential of the electric discharge device 1, the control potential of the grid controlled rectifier is negative by reason of the fact that negative potential is supplied by the secondary section 17 of the transformer 15. The negative potential thus supplied is superimposed on the negative potential provided by the potentiometer 51 and the sum of these two negative potentials is, in general, sufficient to make certain that the grid controlled rectifier 29 is deenergized during the interval during which the negative half wave of principal potential is impressed on the electric discharge device 1. However, when the positive half wave of principal potential is impressed on the electric discharge device 1, the potential impressed by the secondary section 17 between the control electrode 55 and the cathode 35 of the grid controlled rectifier 29 becomes increasingly positive and the negative potential provided by the potentiometer 51 is decreased until such a value of control potential is attained that the rectifier 29 becomes energized. It is to be observed that since in practice the grid controlled rectifier 29 is preferably of the gas-filled type it passes abruptly from a deenergized condition to a fully energized condition.

The grid controlled rectifier 29 is thus energized after the capacitor 23 has been charged and the charge on the capacitor is transmitted therethrough and through the starting electrode 9 and the mercury electrode 5. By reason of the transmission of the current through the starting electrode 9 a discharge is initiated in the electric discharge device 1 and persists substantially until the half cycle of principal potential passes through a zero value and becomes negative.

The operation of the system is illustrated in Figs. 2 and 3. The positive half wave of principal potential is represented by the upper full line curve 61 in each graph. The potential to which the capacitor 23 is charged through the rectifier 29 associated therewith is represented by the horizontal line 63 that is parallel to the axis of abscissa 65 in each graph. The control potentials at which the grid controlled rectifier 29 becomes energized for values of principal potential corresponding to the principal potential of the electric discharge device 1 lie on the lower full line curve 67 which has a slope of polarity opposite to the polarity of the slope of the principal potential curve 61. In accordance with the foregoing nomenclature the curve 67 may be designated as the limiting control potential curve. The limiting control potential corresponding to the potential impressed on the capacitor is represented by a straight line 69 parallel to the axis of abscissa 65 and intersecting the limiting control potential curve 67 at the point 71 that corresponds to the potential impressed on the capacitor 23. The line 69 may be regarded as the limiting control potential curve for the grid controlled rectifier when the capacitor is charged to a value represented by the upper horizontal line 63. The negative control potential that is normally impressed between the control electrode 55 and the cathode 35 of the rectifier 29 by the potentiometer 51 is represented by the lower horizontal line 73 in each plot.

When a positive half wave of principal poten-

tial is impressed on the electric discharge device 1 the control potential impressed on the grid controlled rectifier 29 is represented by the broken line curve 75 which, it will be noted, is simply the upper full line curve 61 representing the principal potential impressed on the electric discharge device 1 added to the lower horizontal line 73 representing the negative control potential provided by the potentiometer 51. The grid controlled rectifier 29, and consequently the electric discharge device 1, are energized approximately at a point corresponding to the point 71 of intersection of the broken line curve 75 and the horizontal line 69 representing the limiting control potential for the grid controlled rectifier 29. The electric discharge device 1 then remains energized during the remaining portion of the positive half cycle. The interval during which the electric discharge device 1 remains energized is represented by the shaded region 79 under the principal potential curve 61.

The graphs shown in Figs. 2 and 3 correspond to two different values of negative control potential, provided by the potentiometer 51. As can be seen in the system represented by the curve shown in Fig. 3, the negative control potential is greater than in the system represented in Fig. 2, and consequently, the electric discharge device 1 is energized later in the cycle in a system such as is represented in Fig. 3 than it is in a system such as is represented in Fig. 2.

Attention is called to the fact that with a system such as is shown in Fig. 1 the output of the electric discharge device can only be controlled for the first half of the half cycle of positive principal potential. The limiting condition is represented by a situation in which the potentials are of such value that the broken line curve 75 is tangent to the straight line 69 representing the limiting control potential of the grid controlled rectifier 29.

To attain control during the complete half cycle of principal positive potential a system such as is shown in Fig. 4 is provided. In this system the phase of the potential impressed between the control electrode 55 and the cathode 35 of the grid controlled rectifier 29 is shifted relative to the principal potential of the electric discharge device 1 and by the shifting of the phase the control during any portion of the half cycle of positive principal potential impressed on the electric discharge device is provided.

In the system shown in Fig. 4 the charging network 51 for the capacitor 23, the discharging network 41 for the capacitor and the other circuits associated with the electric discharge device 1 are substantially the same as the corresponding networks and circuit of the system shown in Fig. 1. However, the control circuit for the grid controlled rectifier 29 is radically different from the corresponding circuit of the system shown in Fig. 1.

An additional section 83 of the secondary 19 of the power supply transformer 15 is provided. The center tap 85 of the secondary section 83 is connected to the anode 31 of the grid controlled rectifier 29 through a suitable resistor 87. The terminal taps 89 and 91 of the section 83 are connected to the terminals of a phase-shifting network 93 comprising a variable resistor 95 and a capacitor 97 connected in series with each other. The junction point 99 of the resistor 95 and the capacitor 97 is connected to the control electrode 55 of the grid controlled

rectifier 29 through the potentiometer 51 of the type utilized in the system shown in Fig. 1.

It is to be noted that the phase of the potential of the junction point 99 of the resistor 95 and the capacitor 97 relative to the potential impressed between the terminal taps 89 and 91 of the secondary section 83 may vary from zero to 180° as the magnitude of the resistor 95 is varied and correspondingly the phase of the potential impressed between the control electrode 55 and the other electrodes 31 and 35 for the grid controlled rectifier 29 is varied relative to the other potentials in the system in the same manner.

The phase-shifting section 83 of the secondary 15 19 may be wound in the same manner as the section 17 of the secondary 19 whereby principal potential is supplied to the electric discharge device 1. Consequently, by varying the resistor in the 20 phase-shifting network of the system, the phase of the control potential may be shifted relative to the principal potential through an angle of 180°. The operation of the system is illustrated 25 in Fig. 5 in which the principal potential of the electric discharge device 1, the principal potential of the rectifier, the limiting control potentials of the grid controlled rectifier 29 and the negative control potential impressed on the grid controlled rectifier 29 are represented in the same manner as the corresponding elements of the 30 system shown in Fig. 1 are represented in Figs. 2 and 3. The control potential is represented by a broken line sine curve 101 built up on the horizontal line 73 representing the negative control potential. As can be seen the broken line curve 35 101 intersects the limiting control potential curve 69 at a point 103 which as far as its time coordinate is concerned lies in the latter half of the positive half cycle of principal potential impressed on the electric discharge device. The 40 electric discharge device 1 is, therefore, energized at this point and remains energized during an interval represented by the shaded area 79 under the principal potential curve 68.

In the system of the type shown in Fig. 1 that 45 I have found particularly useful, the electric discharge device 1 is of the type substantially as shown in Fig. 1 and incorporates a mercury cathode 5, a nickel anode 3, and a starting electrode 9 of boron and boron carbide mixture of 50 which the resistivity is at least .04 ohm per cubic inch and which has a heterogeneous stringy structure. The output potential of the section 25 of the secondary 19 whereby the capacitor 23 is charged is of the order of several hundred 55 volts. The rectifier 27 through which the capacitor 23 is charged is of the gas filled type and is known as the Westinghouse KI-626. The capacitor 23 may vary from .1 microfarad to 16 microfarads, depending on the condition of the 60 starting electrode 9. The grid controlled rectifier 29 is of the type known as the Westinghouse KU-628. The resistor 31 in the discharging network 41 of the capacitor 23 may vary from 2 to 10 ohms. The resistor 59 in series with the 65 control electrode 55 of the grid controlled rectifier 29 and the potentiometer 51 associated therewith is of the order of 25,000 ohms. The principal potential impressed on the electric discharge device 1 is of the order of 110 volts.

70 My invention has been shown herein as applied to particular systems. Specifically, it has been shown as applied to systems in which the electric discharge device transmits only the positive half wave of principal potential impressed 75 thereon. Its application to full wave rectifying

systems is apparent. In such systems the simplest procedure is to apply the same elements to the negative half of the wave of principal potential as are applied to the positive half wave of principal potential and to properly connect the 5 elements of the system for this purpose.

In certain electric discharge devices constructed in accordance with the teachings of the early prior art the discharge is initiated by impressing a potential between the starting electrode and one principal electrode which are normally in contact with each other and then by separating the electrodes to produce a spark. Insofar as my invention applied to devices of this type, it is to be regarded as including within its 15 scope of equivalents, applications to these devices.

Finally it is to be noted that in certain applications of my invention the rectifier 27 in the charging network 51 may be omitted. While in 20 certain connections I have found that the rectifier 27 may be omitted in apparatus in which the starting potential is applied in opposite phase to the principal potential of the electric discharge device 1, the charging network without 25 the rectifier 27 has particular applicability in apparatus in which the charging potential is applied in phase with the principal potential of the electric discharge device. In apparatus of this type the capacitor 23 having been charged 30 negatively is discharged and charged positively during a fractional period of the positive half cycle of principal potential. It is then discharged through the starting electrode 9 during a second interval of the positive half cycle of 35 principal potential. During the negative half cycle of principal potential the capacitor 23 is charged negatively and the following half cycle of positive principal potential is discharged and recharged positively through the windings of the 40 secondary section 25 whereby the charging potential is supplied.

Although I have shown and described certain specific embodiments of my invention, I am fully aware that many modifications thereof are possible. My invention, therefore, is not to be restricted except insofar as is necessitated by the prior art and by the spirit of the appended 45 claims.

I claim as my invention:

1. In combination with an electric discharge device of the type incorporating a plurality of principal electrodes between which an electric discharge is to pass and a starting electrode disposed adjacent to one of said principal electrodes 55 for initiating said discharge; a capacitor, means for charging said capacitor and means, including a second electric discharge device coupled between said capacitor and said starting electrode and providing a discharge path for said capacitor, 60 for coupling said capacitor, after it has been charged, to said starting electrode and said principal electrode adjacent thereto thereby so to discharge said capacitor that a pulse of current is transmitted through said starting electrode and 65 the electric discharge between said principal electrodes is initiated.

2. In combination with an electric discharge device of the type incorporating a plurality of principal electrodes between which an electric discharge is to pass and a starting electrode disposed adjacent to one of said principal electrodes for initiating said discharge; a capacitor, means for charging said capacitor and means, including 70 a second electric discharge device having a con- 75

5 trol electrode and a plurality of principal electrodes, means for coupling said principal electrodes between said capacitor and said starting electrode to provide a discharge path for the charge on said capacitor and means for coupling said control electrode to the principal electrode of said first-named electric discharge device that is most remote from said starting electrode, for coupling said capacitor, after it has been charged, 10 to said starting electrode and said principal electrode adjacent thereto thereby so to discharge said capacitor that a pulse of current is transmitted through said starting electrode and the electric discharge between said principal electrodes is initiated.

15 3. In combination with an electric discharge device of the type incorporating a plurality of principal electrodes between which a discharge is to pass and a starting electrode disposed in contact with one of said principal electrodes to cooperate therewith to initiate said discharge; means for storing electrical charges, means for charging said storing means, and means for discharging said storing means, after it has been charged, said discharging means being so coupled to said starting electrode that a pulse of current is transmitted through said starting electrode and said principal electrode in contact therewith and a discharge between said principal electrodes is initiated.

20 4. In combination with an electric discharge device of the type incorporating a plurality of principal electrodes between which a discharge is to pass and a starting electrode having an electrical resistance that is high in comparison with the resistance of one of said principal electrodes disposed in contact with said principal electrode, and means for impressing an electrical potential between said principal electrodes to cooperate 25 with said starting electrode to initiate and maintain said discharge between said principal electrodes; means for storing electrical charges, means for charging said storing means, and means for discharging said storing means, after it has been charged, said discharging means being so coupled to said starting electrode that a pulse of current is transmitted through said starting electrode and said principal electrode in contact therewith and a discharge between said principal electrodes is initiated.

30 5. In combination with an electric discharge device of the type having a plurality of principal electrodes between which a discharge is to pass and means for initiating said discharge, said means including a mercury electrode and an electrode immersed in said mercury; means for storing electrical charges, means for charging said storing means and means for discharging said storing means, after it has been charged, said discharging means being so coupled to said starting electrode that a pulse of current is transmitted through said mercury and said electrode immersed therein and said discharge between said principal electrodes is initiated.

35 6. In combination with an electric discharge device of the type having a plurality of principal electrodes between which a discharge is to pass and means for initiating said discharge, said means including an electrode having a relatively low electrical resistance and an electrode having relatively high electrical resistance in contact therewith, and means for impressing an electrical potential between said principal electrodes to maintain said discharge; means for storing electrical charges, means for charging said storing

means, and means for discharging said storing means, after it has been charged, said discharging means being so coupled to said starting electrode that a pulse of current is transmitted through said starting electrode and said electrode in contact therewith and said discharge between said principal electrodes is initiated.

40 7. In combination with an electric discharge device of the type having a plurality of principal electrodes between which a discharge is to pass, said electrodes being of such character that a discharge can only pass therebetween when a potential of one polarity is impressed therebetween and cannot pass therebetween when a potential of the opposite polarity is impressed therebetween, and means for initiating said discharge, said means including an electrode having a relatively low electrical resistance and an electrode having relatively high electrical resistance in contact therewith, and means for impressing an alternating electrical potential between said principal electrodes to maintain said discharge; means for storing electrical charges, means including means for impressing a potential across said storing means, for charging said storing means, said means including a plurality of terminals and means for impressing an alternating potential substantially in opposite phase to the potential impressed across said principal electrodes across said terminals, and means for discharging said storing means, after it has been charged, said discharging means being so coupled to said starting electrode that a pulse of current is transmitted through said starting electrode and said electrode in contact therewith and said discharge between said principal electrodes is initiated.

45 8. In combination with an electric discharge device of the type having a plurality of principal electrodes between which a discharge is to pass, said electrodes being of such character that a discharge can only pass therebetween when a potential of one polarity is impressed therebetween and cannot pass therebetween when a potential of the opposite polarity is impressed therebetween, and means for initiating said discharge, said means including an electrode having a relatively low electrical resistance and an electrode having a relatively high electrical resistance in contact therewith, and means for impressing an alternating electrical potential between said principal electrodes to maintain said discharge; means for storing electrical charges, means, including a plurality of terminals, means for impressing an alternating potential substantially in opposite phase to the potential impressed across said principal electrodes across said terminals, current rectifying means and means for connecting said storing means to said terminals through said current rectifying means for charging said storing means, and means for discharging said storing means, after it has been charged, said discharging means being so coupled to said starting electrode that a pulse of current is transmitted through said starting electrode and said electrode in contact therewith and said discharge between said principal electrodes is initiated.

50 9. In combination with an electric discharge device of the type having a plurality of principal electrodes between which a discharge is to pass, said electrodes being of such character that a discharge can only pass therebetween when a potential of one polarity is impressed therebetween and cannot pass therebetween when a potential of the opposite polarity is impressed therebetween, and means for initiating said discharge,

- mercury, means for storing electrical charges, means for charging said storing means and means for discharging said storing means, after it has been charged, said discharging means being so coupled to said starting electrode that a pulse of current is transmitted through said mercury and said electrode immersed therein and said discharge between said principal electrodes is initiated.
16. In combination with an electric discharge device of the type having a plurality of principal electrodes between which a discharge is to pass and means for initiating the discharge, said means including a liquid electrode and an electrode composed of a heterogeneous mass of stringy conductors immersed in said liquid; means for storing electrical charges, means for charging said storage means and means for discharging said storing means after it has been charged, said discharging means being so coupled to said starting electrode that a pulse of current is transmitted through said liquid and said electrode immersed therein, and a discharge between said principal electrodes is initiated.
17. In combination with an electric discharge device of the type incorporating a plurality of principal electrodes between which a discharge is to pass, at least one of said electrodes being normally a liquid, and a starting electrode immersed in said liquid to cooperate therewith to initiate a discharge; means for storing electrical charges, means for charging said storing means and means for discharging said storing means, after it has been charged, said discharging means being so coupled to said starting electrode that a pulse of current is transmitted through said starting electrode and said liquid and a discharge between said principal electrodes is initiated.
18. In combination with an electric discharge device of the type incorporating a plurality of principal electrodes between which a discharge is to pass, at least one of said electrodes being normally a liquid, and a starting electrode immersed in said liquid to cooperate therewith to initiate a discharge; said starting electrode being of a type such that it does not amalgamate with said liquid and is not wetted thereby; means for storing electrical charges, means for charging said storing means and means for discharging said storing means, after it has been charged, said discharging means being so coupled to said starting electrode that a pulse of current is transmitted through said starting electrode and said liquid and a discharge between said principal electrodes is initiated.
19. In combination with an electric discharge device of the type incorporating a plurality of principal electrodes between which a discharge is to pass, at least one of said electrodes being normally a liquid, and a starting electrode immersed in said liquid to cooperate therewith to initiate a discharge, said starting electrode being of a type such that it is not wetted by said liquid; means for storing electrical charges, means for charging said storing means and means for discharging said storing means, after it has been charged, said discharging means being so coupled to said starting electrode that a pulse of current is transmitted through said starting electrodes and said liquid, and a discharge between said principal electrodes is initiated.
20. In combination with an electric discharge device of the type incorporating a plurality of principal electrodes between which a discharge is to pass, at least one of said electrodes being
- normally a liquid, and a starting electrode immersed in said liquid to cooperate therewith to initiate a discharge, said starting electrode having a resistivity that is high in comparison with the resistivity of the liquid; means for storing electrical charges, means for charging said storing means and means for discharging said storing means, after it has been charged, said discharging means being so coupled to said starting electrode that a pulse of current is transmitted through said starting electrode and said liquid and a discharge between said principal electrodes is initiated.
21. In combination with an electric discharge device of the type incorporating a plurality of principal electrodes between which a discharge is to pass, at least one of said electrodes being normally a liquid, and a starting electrode immersed in said liquid to cooperate therewith to initiate a discharge, said starting electrode having a resistivity that is high in comparison with the resistivity of the liquid, is incapable of amalgamating with said liquid and is not wetted by said liquid, means for storing electrical charges, means for charging said storing means and means for discharging said storing means, after it has been charged, said discharging means being so coupled to said starting electrode that a pulse of current is transmitted through said starting electrode and said liquid, and a discharge between said principal electrodes is initiated.
22. In combination with an electric discharge device of the type having a plurality of principal electrodes between which a discharge is to pass, at least one of said electrodes being mercury, and a starting electrode immersed in said mercury; means for storing electrical charges, means for charging said storing means and means for discharging said storing means, said discharging means being so coupled to said starting electrode that a pulse of current is transmitted through said starting electrode and said mercury and a discharge between said principal electrodes is initiated.
23. In combination with an electric discharge device of the type having a plurality of principal electrodes between which a discharge is to pass and means for initiating said discharge, said means including a mercury electrode and an electrode of a material having a resistivity high in comparison with the resistivity of mercury immersed in said mercury; means for storing electrical charges, means for charging said storing means and means for discharging said storing means, after it has been charged, said discharging means being so coupled to said starting electrode that a pulse of current is transmitted through said mercury and said electrode immersed therein and said discharge between said principal electrodes is initiated.
24. The method of initiating a discharge between the principal electrodes of an electric discharge device of the type incorporating a plurality of principal electrodes and at least one starting electrode, said starting electrode being disposed in contact with one of the aforementioned principal electrodes, by means of apparatus which includes a capacitor and means for charging and discharging said capacitor, said method comprising charging said capacitor and passing a current between said starting electrode and the last-mentioned electrode, by discharging said capacitor through the last said electrodes after it has been charged, the maximum magnitude of said current being large enough to ini-

- tiate the discharge between said principal electrodes during an interval of time that is so short that the elements through which said starting current is passed are not deleteriously affected.
- 5 25. In combination with an electric discharge device of the type incorporating a plurality of principal electrodes between which a discharge is to pass and means for initiating the discharge including a plurality of electrodes disposed in contact with each other; a capacitor, means for charging said capacitor and means, including a second electric discharge device in series circuit with said capacitor and said last-named electrodes, for coupling said capacitor, after it has been charged, to said last-named electrodes thereby to discharge said capacitor between said last-named electrodes and to initiate the discharge between said principal electrodes.
- 10 26. In combination with an electric discharge device of the type incorporating a plurality of principal electrodes between which a discharge is to pass and means for initiating the discharge including a plurality of electrodes disposed in contact with each other; a capacitor, means for charging said capacitor and means for connecting said capacitor in a network with said last-named electrodes, the last said means including means for maintaining said network electrically non-conductive while said capacitor is charging and
- 15 until it has been charged to a predetermined difference of potential and means for rendering said network electrically conductive after said capacitor has been charged to said predetermined difference of potential whereby said capacitor is discharged between said last-named electrodes and the discharge between said principal electrodes is initiated. 5
- 20 27. In combination with an electric discharge device of the type incorporating a plurality of 10 principal electrodes between which a discharge is to pass and means for initiating the discharge including a plurality of electrodes disposed in contact with each other; a capacitor, means for charging said capacitor and means for connecting said capacitor in a network with said last-named electrodes, the last said means including means for maintaining said network electrically 15 non-conductive while said capacitor is charging and until it has been charged to a predetermined 20 difference of potential and means, responsive to the difference of potential impressed on said capacitor, for rendering said network electrically conductive after said capacitor has been charged to said predetermined difference of potential 25 whereby said capacitor is discharged between said last-named electrodes and the discharge between said principal electrodes is initiated. 25

LLOYD SMEDE.

DISCLAIMER

2,008,730.—*Lloyd Smeds*, Pittsburgh, Pa. STARTING CIRCUITS. Patent dated July 23, 1935. Disclaimer filed November 12, 1943, by the assignee, *Westinghouse Electric & Manufacturing Company*.

Hereby enters this disclaimer to claim 1 of the patent.
